UNITED STATES PATENT OFFICE.

ALLEN F. KIPPER, OF LOS ANGELES, CALIFORNIA, ASSIGNOR TO RITE HARDWARE COMPANY, OF LOS ANGELES, CALIFORNIA, A PARTNERSHIP CONSISTING OF PRESTON S. WRIGHT AND HAROLD H. TILTON.

DESIGN FOR A KNOB.

Application filed September 18, 1926. Serial No. 19,108. Term of patent 14 years.

To all whom it may concern:

Be it known that I, ALLEN F. KIPPER, a citizen of the United States, and resident of Los Angeles, county of Los Angeles, State of California, have invented a new, original, and ornamental Design for Knobs, of which the following is a specification, reference being had to the accompanying drawing, forming part hereof.

Fig. 1 is a side elevation of a knob showing my new design.

Fig. 2 is a front perspective of the knob showing the new design.

Fig. 3 is a similar front elevation of the knob.

I claim:

The ornamental design for a knob as shown.

ALLEN F. KIPPER.
